C. G. KEMPER.

CORN SHOCKER.

APPLICATION FILED DEC. 22, 1917.

1,262,957.

Patented Apr. 16, 1918.

CHARLES G KEMPER

Attorney

UNITED STATES PATENT OFFICE.

CHARLES G. KEMPER, OF TOWER HILL, ILLINOIS.

CORN-SHOCKER.

1,262,957.

Specification of Letters Patent. Patented Apr. 16, 1918.

Application filed December 22, 1917. Serial No. 208,362.

To all whom it may concern:

Be it known that I, CHARLES G. KEMPER, a citizen of the United States, residing at Tower Hill, in the county of Shelby and 5 State of Illinois, have invented certain new and useful Improvements in Corn-Shockers, of which the following is a specification, reference being had to the accompanying drawings.

10 This invention relates to an improved shock carrier and has for its primary object to provide convenient and serviceable means mounted upon a sulky or other wheel supported vehicle upon which a corn shock may 15 be carried and easily discharged or dumped upon the ground at the desired place, without stopping the movement of the vehicle.

It is another and more particular object 20 of the invention to provide a bundle or shock carrier of the above type including an adjustable support to receive the corn stalks and upon which the stalks are adapted to be arranged in a bundle and suitably tied, and means for mounting said support upon 25 the sulky platform whereby the support may be conveniently moved from a position above the platform to a laterally projecting position, the platform when in the latter position being bodily movable to dump or dis- 30 charge the shock.

It is another important object of my invention to provide simple and effective means for retaining the shock receiving support in position above the platform to receive 35 the shock.

And it is a further general object of the invention to provide a device of the above character, which is relatively simple in its construction, exceedingly strong and durable 40 and capable of manufacture at relatively small cost.

With the above and other objects in view the invention consists in the improved combination, construction and arrangement of 45 the several parts to be hereinafter more fully described, subsequently claimed and illustrated in the accompanying drawing in which similar reference characters designate corresponding parts throughout the 50 several views, and wherein;

Figure 1 is a side elevation showing the shock carrier in full lines in its receiving position and in dotted lines in its discharging position;

55 Fig. 2 is a top plan view;

Fig. 3 is an enlarged section taken on the line 3—3 of Fig. 1;

Fig. 4 is a detail elevation illustrating the latch device for holding the rotatable standard against movement;

Fig. 5 is a horizontal sectional view taken on the line 5—5 of Fig. 4, the standard having been turned through an arc of 90°;

Fig. 6 is a fragmentary plan view showing the adjustable shock supporting member; and

Fig. 7 is a detail vertical section illustrating the means for retaining the shock support in its receiving position with respect to the rotatable standard.

Referring in detail to the drawing 5 designates a platform of suitable length and width which is mounted at its rear end upon an axle 6 having the supporting wheels 7 revolvably mounted upon its opposite ends. 75 The platform is supported at its forward end by a single caster wheel 8. This forward end of the platform is provided with obliquely inclined cutting blades 9 extending in relatively opposite directions from 80 the center of the platform. If desired, a suitable seat indicated at 10 may be mounted upon the platform 5.

A bed plate 11 is secured upon the upper surface of the platform 5 and a vertically 85 disposed bolt or axle 12 is centrally mounted in this bed plate. A standard 13 of elongated U-shape form has its intermediate portion rotatably mounted upon the upper end of the bolt 12. The vertically disposed 90 arms of this standard are rigidly connected adjacent their upper ends by the horizontal bar 14.

15 designates the spaced parallel longitudinal bars of the shock support. The bars at one of their ends are connected to each other by means of the cross bar 16 and at their other ends by a similar cross bar 17. Spaced metal straps 18 have their medial portions secured to the bars 15 on one side 100 thereof and are bent or curved to provide the outwardly projecting bowed arms 19. From these arms the end portions of the arm straps are reversely extended inwardly and have their extremities secured to the 105 bars 15 by the bolts indicated at 20 which also extend through the medial portions of said straps. The extremities of one strap at one end of the support are disposed between the cross bar 16 and the longitudinal bars 15, 110

as clearly seen in Fig. 3. To the upper ends of the arms 19 of this latter strap, suitable brackets or plates 21 are secured to which the ends of a retaining cord for the shock 5 may be tied.

22 designates the intermediate bar of the shock support which is disposed in the plane of the bars 15 and is longitudinally adjustable with respect thereto. This bar 22 is provided 10 with series of spaced openings 23 to receive the bolts 24 which also extend through the metal straps 18. Upon one end of this adjustable bar 22 which projects beyond the ends of the bars 19 an additional 15 bowed metal strap 25 is secured and adjacent to said strap a wire loop 26 is fixed to said bar through which a retaining rope R for the shock is adapted to be passed. The bar 22 may be readily adjusted longitudinally 20 by removing and replacing the bolts 24 as will be readily understood, in accordance with the length of the corn stalks.

The medial portion of a rod 27 is loosely mounted in the angular ends of a bracket plate 28 which is fixed to the bar 17 on one 25 end of the shock support. This rod is bent to provide converging arms the terminals of which are angularly bent in relatively opposite directions and rotatably engaged in the 30 respective arms of the standard 13 as indicated at 29. To each of the bars 15 a latch hook 30 is fixed, and this hook is adapted to extend downwardly over the rear edge of the cross bar 14 connecting the arms of the 35 standard, when the support is in its shock receiving position, as seen in full lines in Fig. 1. These bracket members coact with the bar 14, and serve to prevent the downward swinging movement of the rod 27 and 40 the support with respect to the standard 13 during the loading of material upon the support.

In order to prevent the accidental or casual 45 rotation of the standard and the unintentional discharge of the shock, I provide a lever 31 fulcrumed as at 32 upon the platform 5. One end of this lever is adapted for engagement in a socket or recess 33 in one of the vertical arms of the standard when 50 the standard is in the position shown in full lines in Fig. 1. The lever 31 is urged to this operative position by means of a suitable spring shown at 34. Thus the standard is 55 securely held against casual rotation and the support retained in proper position with respect to the platform to receive the corn stalks in the formation of the shock.

In the operation of my improved carrier, 60 as the stalks are cut, they are gathered by the operator and placed on the support between the bowed arms of the metal straps 18 and 25. When a sufficient number of stalks have been gathered to form a shock, they are bound with suitable twine, and a rope 65 indicated at R is passed through the loop

26 and has its ends connected to the hooked bracket plate 21. The operator now engages the lever 31 with his foot, and releases the standard 13 so that the standard may be turned or rotated through an arc of 90° to 70 swing the shock carrying support to the position seen in dotted lines in Figs. 1 and 2 wherein said support extends laterally from the platform. In this movement, the support is held against vertical tilting by the 75 latch elements 30 as above explained and the shock is secured against downward movement on the support by means of the rope R. One end of this rope is then detached from the bracket 21 and the support is pulled inwardly slightly and then raised and swung outwardly upon the medial portion of the rod 27, thereby moving the shock to a vertical position with the butt ends of the corn stalks engaged upon the ground. The 80 rotatable shock support is then returned to its former position to receive another shock. When the device is to be operated by a single attendant, the shock carrier is mounted upon the platform at one side thereof, as seen in 85 Fig. 2. When however two attendants accompany the machine, the carrier is preferably arranged centrally of the support at its rear end and the shocks are discharged from the rear end of the platform instead of at 90 one side thereof.

From the foregoing description taken in connection with the accompanying drawing, the construction, manner of operation and several advantages of the device will be 100 clearly and fully understood. By means of my invention, after the corn has been harvested, the standing stalks may be readily cut by means of the knife blades 9 and gathered and shocked with a minimum of manual labor. Thus the field may be quickly cleared, the shocks being transported and dumped upon the ground at any convenient place. My improved shock carrier as a 110 whole is of relatively simple construction, strong and durable and highly convenient and serviceable in practical use. It is also manifest that the device can be produced at relatively small manufacturing cost.

While I have herein shown and described 115 the preferred construction and relative arrangement of the several parts, it is to be understood that the device is susceptible of considerable modifications therein and I therefore reserve the privilege of adopting 120 all such legitimate changes as may be fairly embodied within the spirit and scope of the invention as claimed.

Having thus fully described my invention, what I desire to claim and secure by Letters 125 Patent is:—

1. The combination with a wheel supported platform, of a standard rotatably mounted thereon, a swinging member connected to said standard, a shock support pivotally 130

- mounted upon said swinging member, and means for preventing the pivotal movement of the support and the swinging movement of said member in the rotation of the standard.
2. The combination with a wheel supported platform, of a standard rotatably mounted thereon, a swinging member connected to said standard, a shock support pivotally mounted upon said swinging member, means for preventing the pivotal movement of the support and the swinging movement of said member in the rotation of the standard, and additional means for holding the standard against casual rotation in the shock receiving position of the support with relation to the platform.
3. The combination with a wheel supported platform, of a standard rotatably mounted thereon, a swinging member connected to said standard, a shock support pivotally mounted upon said swinging member, and means carried by the support coacting with a part of the standard to prevent pivotal movement of the support and swinging movement of said member in the rotation of the standard.
4. The combination with a wheel supported platform, of a standard rotatably mounted thereon, a swinging member connected to said standard, a shock support pivotally mounted upon said swinging member, means carried by the support coacting with a part of the standard to prevent pivotal movement of the support and swinging movement of said member in the rotation of the standard, and a latch element mounted on the platform to coact with the standard and prevent the casual rotation thereof in the shock receiving position of the support with relation to the platform.
5. The combination with a wheel supported platform, of a U-shaped standard rotatably mounted on said platform, a rod having its terminals rotatably mounted in the arms of the standard adjacent the lower ends thereof, said rod being adapted to swing vertically with respect to the standard, a shock support pivotally mounted upon the medial portion of said rod, a bar connecting the arms of the standard adjacent their upper ends, and means on the support to coact with said bar and prevent pivotal movement of the support and swinging movement of said rod in the rotation of said standard.
6. The combination with a wheel supported platform, of a U-shaped standard rotatably mounted on said platform, a rod having its terminals rotatably mounted in the arms of the standard adjacent the lower ends thereof, said rod being adapted to swing vertically with respect to the standard, a shock support pivotally mounted upon the medial portion of said rod, a bar connecting the arms of the standard adjacent their upper ends, and a latch hook fixed to the support to coact with said bar and prevent pivotal movement of the support and swinging movement of said rod in the rotation of said standard.
7. The combination with a wheel supported platform, of a standard rotatably mounted thereon, a swinging member connected to said standard, a shock support pivotally mounted upon said swinging member, said support including spaced parallel bars and a central bar, means for adjusting the central bar longitudinally with respect to said spaced bars, shock retaining members secured upon said bars, and means for preventing the pivotal movement of the support and the swinging movement of said member in the rotation of the standard.

In testimony whereof I hereunto affix my signature in the presence of two witnesses.

CHARLES G. KEMPER.
